AWNNG

Filed April 30, 1928

UNITED STATES PATENT OFFICE.

OLE G. HERM, OF MARSHALLTOWN, IOWA.

AWNING.

Application filed April 30, 1928. Serial No. 273,893.

This invention relates to awnings of that type having a pliable cover of fabric or similar material, which has its lower edge underlapped to form a loop to receive the awning frame; and particularly to that type provided with a fringe at its lower edge, which fringe is manufactured separately and applied to the cover by sewing, it being desirable to secure the fringe in position by a chain 5 or loop stitch, which is very strong and may be rapidly applied.

The objection, however, to this type of a stitch is that if one of the free ends becomes loosened, then the entire row of stitches may 15 be withdrawn by pulling on the loose end, and for that reason more or less trouble is encountered in properly securing the ends of the thread. The same trouble is experienced when the lock stitch is used, and the present 20 invention relates also to the lock stitch.

It is therefore one of the objects of my invention to provide in connection with an awning cover of the type above described, improved means for securing the ends of the 25 stitches to prevent unraveling of the stitches.

A further object is to provide an improved awning cover which may be easily and quickly applied to the awning frame, and when so applied will be ornamental in appearance and 30 at the same time make strong connection with the frame member on which it is mounted, so that the flapping and vibration of the cover as the awning is moved through the air will not tear or loosen the cover.

35 My invention consists in the construction, arrangement and combination of the various parts of the awning, whereby the objects contemplated are attained, as herein-after more fully set forth, pointed out in my claims, and illustrated in the accompanying drawings, in which:

Figure 1 is a perspective view of my improved awning cover showing the manner in which it is applied to an awning frame of 45 that type designed to be used in connection with automobiles.

Figure 2 is a detail view of a portion of the awning cover and the fringe connected thereto, showing the manner in which the fringe is 50 secured to the cover.

Figure 3 is an inverted view of Figure 2 illustrating the manner in which the chain stitches are positively fastened to the cover.

Figure 4 is a detail inverted sectional view 55 taken on the line 4—4 of Figure 2.

Figure 5 is the same as Figure 4 with the

free edge of the cover folded back to form the loop portion for receiving the frame member.

Figure 6 is a detail sectional view taken on 60 the line 6—6 of Figure 2.

Figure 7 shows a strip of awning material and the manner in which the fringe is attached, and the manner in which the material is cut into strips of a length suitable for the 65 awning frame.

The numeral 10 indicates the upper end 70 of a door or window frame to which the awning frame 11 is secured. Said frame comprises a rod having laterally extending members 12 and a longitudinally extending member 13. A roller 14 is secured to the upper end of the frame 10.

The said frame 11 and the roller 14 are of the ordinary construction, and designed to 75 support an awning cover 15 which may be constructed of flexible water-proof material. The cover 15 is provided with a loop portion 16 for receiving the member 13, said loop portion being formed by underlapping the lower 80 edge of the cover and securing the said underlapped portion in position by means of a row of lock stitches 17, which is run a slight distance from the free edge 18 of the member 16.

85 The free edge 18 is secured to the under face of the body by means of a flexible cement 19, of a composition that will unite with the composition of which the cover member is formed, so that the said free edge and the body are permanently fixed together, thereby preventing the said free edge from turning back and weakening the stitches 17. A portion of the cement will run into the 90 stitches 17 and permanently fix the stitches 95 to prevent unraveling.

For ornamental purposes a fringe 20 is applied to the loop portion 16 by means of a double row of chain stitches 21, said fringe being applied to the outer surface of the cover 100 with the looped ends of the stitches adjacent to the inner surface of the cover, as illustrated in Figure 3, after which the said looped portions are permanently fastened to the inner face of the cover by means of a layer of 105 thin flexible cement 22, said cement permanently fastening the loops to the fabric, so that if one of the loops should become broken or worn, the stitches will not unravel.

I find that there is a material saving in the 110 cost of construction by this method. In the actual construction of the awnings, the mate-

rial from which the awning covers are made is manufactured in long strips of a width equal to the perpendicular width of the awning. The fringe is also manufactured in long strips and is applied to the strip of awning material, as illustrated in Figure 7, by running the strip and fringe continuously through a sewing machine, after which the material is inverted, in the manner shown in Figure 4, and the cement applied to the loop portions of the stitches. The said strip may then be cut transversely in any desired lengths, as indicated by dotted lines in Figure 7, thereby providing means whereby the awnings may be easily and quickly manufactured, and at the same time preventing the free ends of the loop portions of the stitches from unraveling.

This is a very important feature, inasmuch as a great deal of difficulty has been experienced in manufacturing these awnings in individual lengths, as the free ends of the threads must be fastened by restitching a number of times or tying the ends of the thread. In either case the stitches would unravel if one of the intermediate loop portions should become broken.

I claim as my invention:

1. A strip of fabric secured to a second strip of fabric by a row of stitches, the loop portions of said stitches being permanently secured to the adjacent fabric by a flexible cement to prevent unraveling of said stitches.

2. A strip of fabric secured to a second

strip of fabric by a row of stitches, the free ends of said row of stitches being permanently secured to the adjacent face of said fabric by cement to prevent unraveling thereof.

3. An awning cover comprising a strip of awning fabric, a fringe secured to the outer face of said fabric near one edge by a row of chain stitches, the loops of said stitches being adjacent to the inner face of said fabric and permanently fixed thereto by a flexible cement.

4. An awning cover comprising a strip of awning fabric, a fringe secured to the outer face of said fabric near one edge by a row of chain stitches, the loops of said stitches being adjacent to the inner face of said fabric and permanently fixed thereto by a flexible cement, the outer portion of said fabric from said stitches being underlapped and secured to the body by a row of lock stitches near its edge.

5. An awning cover comprising a strip of awning fabric, a fringe secured to the outer face of said fabric near one edge by a row of chain stitches, the loops of said stitches being adjacent to the inner face of said fabric and permanently fixed thereto by a flexible cement, the outer portion of said fabric from said stitches being underlapped and secured to the body by a row of stitches and flexible cement near its edge.

Des Moines, Iowa, April 25, 1928.

OLE G. HERM.
